ATTORNEY.

UNITED STATES PATENT OFFICE.

BARTON P. JENKS, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A LIQUID-SHAKER, THERMOS BOTTLE, OR SIMILAR ARTICLE.

48,788.

Specification for Design.

Patented Mar. 28, 1916.

Application filed December 17, 1915. Serial No. 67,478. Term of patent 14 years.

To all whom it may concern:

Be it known that I, BARTON P. JENKS, a citizen of the United States, residing at Providence, in the county of Providence and State of Rhode Island, have invented a new, original, and ornamental Design for a Liquid-Shaker, Thermos Bottle, or Similar Article, of which the following is a specification, reference being had to the accompanying drawings, forming part thereof.

The figure in the drawing is a front view

of the liquid shaker, thermos bottle, or similar article showing my design.

I claim

The ornamental design for a liquid shaker, thermos bottle, or similar article, as shown.

BARTON P. JENKS.

Witnesses:

ADA E. HAGERTY,
J. A. MILLER.
